CLAIM

The ornamental design for a coin sorter, as shown and described.

DESCRIPTION

FIG. 1 is a perspective view taken from the top, front and right side of a coin sorter embodying our new design;

FIG. 2 is a left side elevational view thereof;

FIG. 3 is a top plan view thereof;

FIG. 4 is a right side elevational view thereof;

FIG. 5 is a front elevational view thereof; and,

FIG. 6 is a rear elevational view thereof.

FIG. 1

FIG. 2

FIG. 3

FIG. 4

FIG. 5

FIG. 6

UNITED STATES PATENT AND TRADEMARK OFFICE
CERTIFICATE OF CORRECTION

PATENT NO. : Des. 359,152

DATED : June 6, 1995

INVENTOR(S) : Thomas P. Adams and John B. Ledingham

It is certified that error appears in the above-identified patent and that said Letters Patent is hereby corrected as shown below:

Title Page:

The following special descriptive paragraph is added below the figure descriptions of the CLAIM field (57):

--The fragmentary broken line representations of control surfaces in Figs. 1, 3 and 5 and of a table in Figs. 1 and 2 are for the purpose of illustration only and form no part of the claimed design.--

Signed and Sealed this

Twenty-second Day of August, 1995
